RECORDING OF ELECTRICAL IMPULSES

Edward W. Kellogg, Moorestown, N. J., assignor
to Radio Corporation of America, a corporation
of Delaware

Application June 30, 1939, Serial No. 282,287

2 Claims. (Cl. 179—100.3)

This invention relates to the recording of electrical impulses such as those of audio frequency, and has for its principal object the provision of an improved apparatus and method of operation for producing variable density push-pull records of the noise reduction type.

The present invention is related to that of Dinnick U. S. Patent 2,095,317 in that it involves utilization of a penumbra shadow. It is similar to that of Dinnick U. S. Patent 2,095,318 in that it involves the production of a variable density push-pull record of the noiseless type, but differs therefrom with respect to the means whereby the oppositely shaded penumbra shadows are adjusted transversely of the light slit in accordance with the volume of the sound to be recorded. It involves certain structural features like those disclosed by a copending application of Underhill, et al., Serial No. 210,592, filed May 28, 1938, now U. S. Patent 2,268,097, issued December 30, 1941, and assigned to the same assignee as the present application.

In accordance with the invention, a light beam of an intensity varying gradually between opposite beam edges is split into two components which are oppositely shaded and are vibrated about zero or rest positions determined by the volume or level of the recorded impulses. To this end, a prism or the like may be arranged to separate and reverse one of the beam components, and the position about which both component beams are vibrated at the light slit of the recorder may be determined by the position of a penumbra mask maintained in a position dependent on the level of the recorded impulses. Thus, when the impulse level is relatively low, the low intensity edges of the component beams are biased to a position relatively close to the light slit, and when the impulse level is relatively high these edges are biased to a position more remote from the light slit.

The invention will be better understood from the following description considered in connection with the accompanying drawing, and its scope is indicated by the appended claims.

Referring to the drawing:

Figure 1 illustrates the optical features of the invention.

Figure 2 is a wiring diagram illustrating certain electrical features of the invention.

Figure 3 illustrates the zero or rest positions of the oppositely shaded component light beams when the amplitude of the recorded impulses is relatively high.

Figure 4 illustrates the rest positions of the

component beams when the impulse amplitude is relatively low, and

Figure 5 is an explanatory diagram relating to the function of a reversing prism which forms a part of the optical system.

The system of Fig. 1 includes a light source 10, from which light is projected through a spherical lens 11, the aperture of a plate 12, a prism 13, a cylindrical lens 14, and a spherical lens 15 to the vibratory reflector 16 of a galvanometer or other suitable recording device. From the reflector 16 an image of the source 10 is reflected through a lens 17, the light slit 18 of a plate 19, and a lens 20 to the record 21 upon which the impulses are to be recorded. In the vertical plane, lenses 16 and 17 bring aperture 12 into sharp focus on the plate 19.

Interposed between the aperture plate and the prism 13 are a fixed mask 22 and a movable penumbra mask 23. Since the penumbra mask 23 is not sharply focused on the slit plate 19, it causes a penumbra, or soft-edged shadow at the slit 18. As this light of graduated intensity is moved up and down across the slit 18 by the movements of the mirror 16, the intensity of the light image of the slit on the film varies in accordance with the deflections of the galvanometer mirror 16, and thus produces a sound record of the variable density type. As previously indicated, the mask 23 is biased to a position dependent on the amplitude or volume of the impulses to be recorded, this position being dependent on the current of the shutter-operating coil 24. The reflector 16 is, of course, vibrated in accordance with the electrical impulses applied to the galvanometer-operating coil 25.

As has already been explained, the shutter 22 would cause the light applied to the reflector 16 to be in the form of a penumbra shadow which would gradually increase in intensity as the top of the reflector is approached. Such a shadow vibrating transversely of the slit 18 would produce on the record 21 a single sound track of the variable density type. In order to produce a push-pull record, the prism 13 is arranged to intercept and reverse one side of the penumbra shadow. Such a prism, the action of which is illustrated in Fig. 5, has the property of reversing or inverting the image of the aperture and shutter vane, but also reverses the direction of motion of the image of the latter. An equalizing plate 13a extending from or disposed contiguous to the prism 13, as shown in Figure 1, transmits the other half of the penumbra shadow without inversion and also serves to equalize the

intensity or brightness of the two beam parts. As a result, there is produced at the light slit 18 a pair of oppositely shaded light beams such as illustrated at 26 and 27 in Figs. 3 and 4, the component 27 being reversed by the prism 18 as indicated by Fig. 5. When the shutter vane 23 moves, the two shaded light beams 26 and 27 move in opposite directions.

The positions to which the corresponding low-intensity edges of the beams 26 and 27 are biased with respect to the slit 18 are, of course, dependent on the current of the coil 24. They are biased to positions relatively far away from the slit 18 when the current of the coil 24 is high, and are biased to positions relatively close to the slit when the current of this coil is relatively low.

In order that the two components of the push-pull sound track may be readily reproduced, it is desirable that they be slightly spaced from one another. For the purpose of producing this desired spacing, an elongated mask 28 is provided, located in the optical axis 29 of the system. It will be noted that the stationary mask 22 has its upper edge located at the optical axis 29, and functions as a stop which prevents the penumbra shadow from moving beyond a certain point which is the optimum position for high modulation. Movement of the shutter 23 above the upper edge of the shutter 22 in response to decrease in the volume of the recorded impulses, of course, functions to shift the penumbra shadows so that the slit illumination is decreased in intensity, as shown in Fig. 4, compared with Fig. 3.

The wiring diagram of Fig. 2 illustrates in schematic form the electrical connections of the apparatus. Thus, sound is picked up and converted into corresponding electrical impulses by a microphone 30, and these corresponding electrical impulses are amplified by an amplifier 31 and supplied to the operating coil 24 through which the reflector 18 is vibrated. A part of the

output of the amplifier 31 is supplied, through an amplifier, a rectifier and a filter, indicated generally at 32, to the coil 24 which determines the position of the penumbra shutter 23. It should be understood that the amplifier, rectifier and filter circuits function to produce in the coil 24 a direct current which varies in value in accordance with the envelope of the recorded impulses. Otherwise stated, the current in the coil 24 varies as the volume or amplitude of the recorded impulses, and the stationary mask 22 limits the biasing effect of this current so that it produces no optical effect beyond a value sufficiently large to move the shutter 23 below the upper edge of the shutter 22.

I claim as my invention:

1. In an electrical impulse recording apparatus, the combination of means for producing a single light beam, means for thereafter producing two light beams from said single beam, said second named means including a portion adapted to reverse a part of said single beam and another portion adapted to transmit the remaining part of said single beam without reversal, means for vibrating said two light beams in accordance with the impulses to be recorded, and supplementary means for moving said two beams in accordance with the strength of said impulses.
2. The invention set forth in claim 1 characterized in that said second named means comprises a prism adapted to reverse a light beam transmitted thereby, and a plane light transmitting member contiguous thereto adapted to transmit a light beam without reversal, said prism and plane member being so disposed relative to said single light beam that said prism transmits and reverses a part of said single beam while said plane member transmits the remaining part of said single beam without reversal.

EDWARD W. KELLOGG.
